DORIS V. BELKNAP, OF BROOKLYN, NEW YORK, ASSIGNOR TO MONUMENT MILLS, OF HOUSATONIC, MASSACHUSETTS, A CORPORATION OF MASSACHUSETTS

DESIGN FOR BEDSPREAD

Application filed February 7, 1930. Serial No. 34,448. Term of patent 7 years.

To all whom it may concern:

Be it known that I, DORIS V. BELKNAP, a citizen of the United States, residing at 780 St. Marks Avenue, Brooklyn, county of Kings, and State of New York, have invented a new, original, and ornamental Design for Bedspread, of which the following is a specification, reference being had to the accompanying drawing, forming part hereof.

The drawing is a plan view of a bedspread showing substantially one fourth of the design in detail. Except for the center motif which is shown complete, the detailed illustration, contained between the dot and dash lines a—a and the marginal edges comprises one quarter section of the design, the same being repeated in the other three quarters in proper relation thereto.

I claim:

The ornamental design for bedspread as shown and described.

DORIS V. BELKNAP.
